UNITED STATES PATENT OFFICE.

OSCAR WINTER, OF PHILADELPHIA, PENNSYLVANIA.

TABLE PAD.

Application filed February 12, 1924. Serial No. 692,255.

The main object of the invention is the provision of a table pad the body of which is comprised of a plurality of superimposed layers, two or more, disposed in different 5 and parallel planes, one layer being detachably secured to a layer or layers in a different plane or planes so that, when injured or excessively soiled, it can be removed and another similar layer substituted easily and 10 at small cost.

A further object is the provision of a pad, of the general character set forth, formed of sections hinged together, individual layers of which sections, or an individual 15 layer of a section, can be detached and others or another substituted.

A further object is the provision of a pad, as last set forth in which a detachable layer is made slidable as well as detachable so it 20 can be moved away from and towards the hinge uniting two sections.

Folding pads heretofore constructed have been unsatisfactory by reason of the cracking of the surface cover and the formation 25 or development of creases, wrinkles and fullnesses therein which present surface obstructions to dishes or glasses moved relative to the same. Such pads after a short period of use become unsightly and objectionable and if recovered at considerable 30 expense soon develop the same objectionable cracks, folds and wrinkles. To eliminate these objectionable features and produce a pad having a constant smooth surface, one 35 which can easily and cheaply be repaired should it become necessary, and which will be serviceable for a long period of time, is the general purpose of the present improvements.

40 The invention consists in certain novelties of construction and in the combination of parts as herein set forth and claimed.

The accompanying drawings illustrate one 45 example of the embodiment of the invention, the parts being constructed and combined according to the best mode of procedure I have so far devised for the purpose.

Figure 1 is a top plan view of a pad having three sections hinged together so it 50 can be folded, certain parts normally invisible being indicated by dotted lines.

Figure 2 is an enlarged sectional view of Figure 1 on line 2—2.

Figure 3 is an enlarged sectional view on 55 line 3—3 of Figure 1.

Figure 4 is an enlarged sectional view on line 4—4 of Figure 1.

Figure 5 is a sectional view similar to Figure 4 with the top slideable layer shifted to the left away from the hinge. 60

Figures 6 and 7 are views of one of the detachable fastening means, four being shown, the part shown by Figure 6 being secured to the movable layer and the part shown by Figure 7 being secured to the 65 fixed or lower layer of the section.

Figure 8 is a top plan view of a lower layer of a section, the top layer being removed.

Figure 9 is a top plan view of the top 70 or movable layer with parts thereof broken away to show the construction in different parallel planes.

Figure 10 is a plan view of the paperoid covering for the movable layers detached, 75 also showing the edge thereof which is to be turned under.

Figure 11 is a section of Figure 1 on line 11—11.

Figure 12 is a top plan view of the paperoid covering or sheet for the middle section, also showing the edge which is to be turned under. 80

Figure 13 is a sectional view similar to Figure 11, showing the covering or sheet 85 partly removed.

Note that in Figure 1 the left hand section folds to the right over and upon the middle section, the hinge 1 being part of the covering 3 of ornamental soft fabric 90 extending beneath all three of the sections, and that the section at the right folds over beneath and upon the middle section, the hinge 4 being of paperoid folded as shown in Figure 2 to a U shape with its free edges 95 secured preferably by glue or cement to the bottom layers of the middle and end sections.

Each of the lower layers of the three sections is of substantially the same construction, to wit: A sheet of non-heat-conducting material 5, as wool felt, and a sheet of porous non-heat-conducting material 6 formed of two sheets of cardboard with a corrugated sheet of cardboard between them 100 united by glue or otherwise, the covering fabric 3 extending beneath all three sections and the edges 7 of the same turned over upon the material 6 at its edges and secured in place by glue or cement. Above the hinge 105 110

1 is inserted a strengthening strip of fabric 8 having its edges glued or cemented to a side and middle section. Above strip 8 is a strip of paperoid 9 which is waterproof to prevent the passage of spilled liquid.

The middle section has, besides the lower layer described, a sheet of cardboard 10 with its central portion within the dotted line indicated by Figure 1 secured to the lower layer by glue or cement, the outer edge all the way around being free, a removable paperoid cover 11, and a loose sheet of cardboard 12, the curved edge of the paperoid cover being slotted at 13 and all four edges turned over and extended beneath the free edges of the cardboard 10, the cardboard 12 being inserted to make the central section of the same thickness as the two hinged sections. Obviously, the paperoid cover, which is impervious to water and can be washed without injury, may easily be removed should it become injured and another similar cover be substituted.

The side wing or hinged sections are of similar construction, each having a detachable layer, and one will be described:

The bottom layer of each folding hinged section has been described as constructed of sheets 5 and 6. The top removable layer comprises two sheets of cardboard 14 and 15 and the paperoid covering 16 having its curved edge 17 slotted as shown in Figure 10 so the entire edge can be turned over and under the outer edges of the two sheets of cardboard 14 and 15. To detachably secure the layer as a whole to the lower layer of the section detachable interlocking fastening means are preferably used, in this instance four of them being shown, and an example of fastening means is illustrated by Figures 6 and 7. The part shown by Figure 7 consists of two sheet metal clips struck up to have prongs 18 and a wire bar 19 uniting the two clips. This part is secured to the sheet 6 by the prongs so the bar 19 will be disposed within a cut-out opening or hole 20 made in the sheet 6, as shown. The other part shown by Figure 6 is also of sheet metal struck up to form prongs 21 and curved spring tongues 22 which slip over the bar 19 and interlock therewith. This part is secured by the prongs 21 to sheet 14 which has a hole 23 in it through which the spring tongues extend, as shown. Note that the holes or cut-out openings 20 in the sheet 6 are large enough to allow the tongues 22 to slide relative to the bars 19. Obviously, when the top detachable layer of a section is in place it can slide as a whole towards the hinge between the wing section and the middle section and close the space or joint between them so there will be a smooth, even top surface throughout. Also, see Figure 5, the entire top layer can be slid or shifted away from the line of the hinge when the

side section is to be folded over upon the middle section. A tape 2 is attached to the shiftable layer which may be used to move the same in one direction.

The paperoid coverings mentioned are specially made tough and flexible and impervious to water so they can be washed when soiled, and soap and other cleaners will not injure the exposed surface. Should a covering become injured or excessively worn it can easily and quickly be removed and another substituted at small cost.

When unfolded and the layers of the wing or side sections slid inwardly there will be no appreciable open spaces between the sections, and the top surface will be smooth without folds, wrinkles or projections of any kind.

While I have shown one example of detachable fastening means for the removable layers, I do not restrict the scope of the invention to such means, as other means for the same purpose may be substituted.

From the example of the embodiment of the invention as shown and described it will be clear that I have produced a pad which fulfills the conditions set forth as the purpose or object of the invention. Other examples displaying modifications in the layers, sheets, coverings, sections, hinges and fastenings may embody the improvements without constituting substantial departures.

What I claim is:

1. A table pad comprised of a plurality of separate superimposed layers of material, secured together and means located inside the outer edges of two of said layers and at their adjacent surfaces for detachably securing one of said layers in its superimposed position.

2. A table pad comprised of a plurality of separate superimposed layers of materials and means located at the adjacent surfaces of said layers for detachably and slidably connecting one of said layers to another layer.

3. A table pad having a plurality of sections hinged together, one of the sections being comprised of separate superimposed layers of material and one of the layers detachably secured to the other by means located at the adjacent inner surfaces of the layers.

4. A table pad having a plurality of sections hinged together, one section comprised of a plurality of separate superimposed layers of material, and one of said layers being detachably and slidably connected to another layer by means located at their adjacent meeting surfaces.

5. A table pad comprised of a plurality of separate superimposed layers of material one of said layers being detachably secured to another layer by means located between said two layers.

6. A table pad comprised of a plurality of

separate superimposed layers of material, one of said layers being secured to another by separable interlocking devices.

7. The subject-matter of claim 6 when each of said separable interlocking devices consists of parts one of which is slidable relative to another.

8. A table pad comprised of a plurality of separate superimposed sheets of material, one of said sheets being secured to an adjacent sheet at its central area so as to leave the edges free, and a waterproof covering having its edges turned under said free edges to detachably hold the same in position.

9. A table pad comprised of a plurality of separate layers of material, one layer being detachably secured to another at its central area only so as to leave the outer edges thereof free and a waterproof covering for said layer having its edges turned under the edges of said layer to hold the covering in place.

10. A table pad having sections hinged together, one of said sections comprised of 25 a plurality of separate superimposed layers of material, one of said layers being provided with a covering and said layer and covering detachably and slidably secured to another layer.

11. A table pad comprised of a plurality of separate superimposed layers of material disposed in parallel planes, one of said layers having a water-proof covering, and means for detachably securing said layer 35 having said covering to an adjacent layer, said means being located at adjacent surfaces of said layers and inwardly of their outer edges.

12. The subject-matter of claim 11 when the said covering is detachably secured to said detachable layer.

In testimony whereof I affix my signature.

OSCAR WINTER.
